MITTEN

George A. Whittaker, Los Angeles, Calif.

Application December 24, 1948, Serial No. 150,353

Term of patent 14 years

(Cl. D3—11)

To all whom it may concern:

Be it known that I, George A. Whittaker, a citizen of the United States, residing at Los Angeles, in the county of Los Angeles and State of California, have invented a new, original, and ornamental Design for a Mitten, of which the following is a specification, reference being had to the accompanying drawing, forming part thereof.

I claim:

The ornamental design for a mitten, substantially as shown.

GEORGE A. WHITTAKER.
